UNITED STATES PATENT OFFICE

NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

DESIGN FOR A LENS STRAP

Application filed July 30, 1932. Serial No. 44,487. Term of patent 14 years.

To all whom it may concern:

Be it known that I, NELSON M. BAKER, a citizen of the United States, residing at Southbridge, in the county of Worcester and State of Massachusetts, have invented a new, original, and ornamental Design for a Lens Strap, of which the following is a specification, reference being made to the accompanying drawing, forming a part thereof.

The figure is a perspective view of a lens strap, showing my new design.

The outside of the second or inner ear is ordinarily ornamented in the same manner as the one shown, although if desired it may be left plain and unornamented, as it cannot be seen from the front when the device is in use on the face of a wearer.

I claim:

The ornamental design for a lens strap substantially as shown and described.

In testimony whereof, I affix my signature.

NELSON M. BAKER.
